UNITED STATES PATENT OFFICE.

GOTTLIEB W. VOLZ, OF LONG BEACH, CALIFORNIA, ASSIGNOR, BY MESNE ASSIGNMENTS, OF ONE-HALF TO WILLIAM J. BOWMAN, OF LOS ANGELES, CALIFORNIA.

COMBINATION OIL AND GAS CARBURETOR.

Application filed October 8, 1924. Serial No. 742,412.

My present invention is a combination device designed to effect a carbureting of air with either a gaseous or a liquid fuel; and it is an important feature of this invention which comprises means whereby, when gas pressure drops, a carburetor supplying fuel to a boiler, or the like, may automatically be fed with liquid fuel, and whereby any subsequent restoration of gas pressure is effective automatically to cut off the supply of liquid fuel and to restore the flow of gaseous fuel; and the gas supply pipe may also optionally be so controlled, by automatic means, and concurrently with a control of steam, introduced as an entrainment fluid, as to maintain a predetermined steam pressure, for use as required.

Other objects, including liquid fuel level control and preheating means, and an injector comprised in a novel carbureting organization, and means for maintaining a pilot flame, and additional subsidiary features hereinafter referred to, will be understood from the following description of an illustrative embodiment of my invention, taken in connection with the appended claims and the accompanying drawings, in which—

Fig. 1 is a somewhat diagrammatic general elevational view showing the relationship of my novel carbureting device to a steam boiler plant in connection with which the same may be used.

Fig. 2 is a plan view of a typical carbureting organization illustrating my invention.

Fig. 3 is an elevational view which may be regarded as taken from the direction indicated by the arrow 3 of Fig. 2.

Fig. 4 is an elevational view, with parts in section, showing the interior construction of a carburetor float chamber provided with means for preheating oil to be used as a liquid fuel, this element being hereinafter referred to as an oil-conditioning regulator.

Figs. 5, 6 and 7 are sectional views showing diagrammatically certain details of carburetor construction and connections.

Fig. 8 is a diagrammatic view illustrating the principles of operation of a boiler installation to which my invention may be applied.

Referring to the details of that specific embodiment of my invention chosen for purposes of illustration, B may be a boiler or boilers, heated by the combustion of a fluid

fuel mixture piped thereto from a carburetor C; and this carburetor may include an injector I connected both with a supply of steam, to serve as an entrainment fluid and with means for admitting either a combustible gas from a gas main M, or a combustible oil, from an oil main O (see Figs. 1 and 8); and 11 may be an oil-conditioning regulator, within which oil may be pre-heated on its way to the carburetor C.

At 12 I may provide a steam-controlled gas feed regulator comprising a diaphragm D (see Fig. 8), connected with a rod R adapted directly to open a gas valve V, to control the flow of combustible gas to a gas feed pipe 13; and the rod R may be pivotally connected to a lever L, provided with means such as a link 14, carrying a turn buckle 14', for the automatic adjustment of a balanced valve 15, through which steam, to serve primarily as an entrainment fluid may be supplied to the injector carburetor C, the construction here referred to being such that any diminution in steam pressure above the diaphragm D may serve simultaneously to increase the opening of both the valve V and the balanced valve 15, thereby increasing the flow of both gas and steam, with a consequent intensification of the flame projected beneath the boiler B, to restore the steam pressure to a predetermined level.

At 16, I show, in the path by which steam is delivered to the injector I, a fitting in the form of a cross providing a clean-out or inspection opening and having connection 90 permitting a flow of gas thereto from the main M, for the maintenance of a pilot flame beneath the boiler or boilers B, even when gas pressure is low and optionally when steam is cut entirely off from the injector I; and at 17 I show an automatic check valve adapted to prevent flow of gas, when gas pressure is high, into pipes by which preheated oil may alternately be fed to the carburetor C, to which the gas feed pipe 13 is also connected.

18 is an opening through which air may be admitted to the carburetor C, which is shown as comprising the central injector tube through which steam may be admitted; and when gas is prevented, as by the closing of the valve 20 having a hand wheel 20', or by a diminution in gas pressure in the main M, from entering the carburetor C by way of the pipe 13, the air

admitted through the pipe 18 may be carbureted by liquid fuel advancing to the injector I in consequence of a diminution in pressure above the check valve 17, assuming the supply of steam or other entrainment fluid, through the balanced valve 15 to continue; and in order that no diminution in gas pressure shall result in a flow of steam into the main M, a check valve 19 may be interposed in the pipe 21, shown as provided also with a regulating valve 21' having a hand wheel 21'', through which valves gas may normally enter the cross 16, for use as already described.

15 Oil delivered through the conditioning regulator 11, or its equivalent, may be pre-heated by steam introduced into a lower compartment thereof by a pipe 22, this pipe being shown as provided with a regulating hand valve 22', a separate pipe 23 being preferably employed to carry steam from the boiler B to the mentioned gas feed regulator 12; and heated oil delivered from the conditioning regulator 11 to an oil feed pipe 24, shown as provided with a regulating hand valve 24' in addition to the mentioned check valve 17, may be thereby fed to the injector I of the carburetor C at a suitably elevated chamber, favorable to the 30 efficient carbureting of the same.

The carburetor C may comprise a housing 25 into which the mentioned air inlet 18 may be connected at right angles; and it may be closed at one end by a cap 26 having threaded engagement permitting relative adjustment, the outlet end of the housing 25 being connected with a pipe or pipes 27 through which the carbureted mixture may be delivered to burners beneath the boiler or boilers B. The carburetor C may comprise also an injector nozzle 30, shown as provided with a constriction 30' and toward which may extend the exit end of a pipe 31, shown as adjustable therein by the rotation of a hexagonal body 31' and to which steam or gas may be admitted from the mentioned cross, connected with the balanced valve 15 by means of the pipe 15'.

Oil to be delivered from the regulator 11, or its equivalent, to the carburetor C, as by way of the pipe 24, may be fed to said regulator by an inlet pipe 32 shown as extending upwardly through a partition 32' which serves to confine a steam chamber into which the mentioned steam pipe 22 extends; and means such as a float 34, having a rod 35 shown as extending through the inlet pipe 32 may be provided in a steam-heated float chamber 34', the lower end of the rod 35 being shown as provided, with a ball 36, fitting a seat 37, automatically to maintain a predetermined level in the pipe 24, or its equivalent, relatively to the carburetor C; and in order to maintain the parts of this carburetor in their adjusted relationships, I

may provide the threaded connections therebetween with locking means such as the nuts 40, 41, the former engaging the cup 26, and the latter engaging a bushing 48 by which the ejector pipe 31 may be centered within 70 a cross 49 with which the gas feed pipe 13 and the oil feed pipe 24 are respectively connected; and the same steam which is used in the preheating of oil within the float chamber 34' may optionally be fed through 75 the balanced valve 15, as by means of a connecting pipe 47, optionally provided also with a regulating valve having a hand wheel 47'. The exit end of the pipe 31 may be provided, as best shown in Figs. 6 and 7, 80 with inclined slot 49', adapted to impart a whirling motion to the oil or gas entrained by the steam or other fluid delivered under pressure therethrough; and it will be obvious that the delivery or non-delivery of oil 85 by way of the oil feed pipe 24 containing the check valve 17, assuming a suitable flow of steam, or the like, through the pipe 31, will be dependent upon whether or not the pressure of gas in the gas feed pipe 31 90 (which pressure may be dependent upon that in the main M, assuming the valve V to be kept open by a fall in the boiler pressure) is so low as to permit the upward opening of the check valve 17. Thus, when the gas pressure in the main M is adequate 95 steam pressure may be maintained by the burning of gas; and whenever the gas pressure in the main M falls below a predetermined value, preheated oil may be automatically fed as an alternative fuel, to maintain a predetermined boiler pressure and to provide steam for any engines or other machinery which may be supplied therewith, as through the pipe 50, or its equivalent. 100 During the burning of gas, it will be obvious that my invention provides means for the simultaneous and automatic regulation of the feed of gas and steam to my carburetor; and the alternative connections including the pipe 21 provide means for the maintenance of a pilot flame even when the oil supply and the steam supply to the carburetor are entirely cut off.

110 Although I have herein described a single embodiment of my invention, it will be understood that various features thereof might be independently employed, and also that additional modifications might be made by those skilled in the art, without the slightest departure from the spirit and scope of my invention, as the same is indicated above and in the following claims.

I claim as my invention:

125 1. A system for the maintenance of steam pressure comprising: a boiler; means for burning a carbureted mixture thereunder, a carburetor provided with both a fluid fuel feed pipe and a gaseous fuel supply pipe, as well as a nozzle for the delivery of an en- 130

ainment fluid; and means comprising a balanced valve, responsive to steam pressure, for controlling the flow of said entrainment fluid to said carburetor so as substantially to compensate for deficiencies in the delivery of said gaseous fuel thereto.

2. A system for the maintenance of steam pressure comprising: a boiler; means for burning a carbureted mixture thereunder; a carburetor provided with both a fluid fuel feed pipe and a gaseous fuel supply pipe, as well as a nozzle for the delivery of an entrainment fluid; and means comprising a balanced valve, responsive to steam pressure, for controlling the flow of said entrainment fluid to said carburetor, said balanced valve being mechanically interconnected with means for controlling a fluid fuel supply to said carburetor, and said

fluid fuel feed pipe being provided with means to prevent undesired advance of gas therethrough at times of high pressure.

3. A system for the maintenance of steam pressure comprising: a boiler; means for burning a carbureted mixture thereunder; a carburetor provided with both a fluid fuel feed pipe having a valve, and a gaseous fuel supply pipe, as well as a nozzle for the delivery of an entrainment fluid; and means whereby a fall in steam pressure may cause a simultaneous opening of said valve in said fluid fuel feed pipe and an increased flow of said entrainment fluid to said carburetor.

In testimony whereof, I have hereunto set my hand at Los Angeles, California, this 1st day of October, 1924.

GOTTLIEB W. VOLZ.
